PSEUDO-EXTENSION OF FREQUENCY BANDS

Louis A. De Rosa, Dayton, Ohio

Application October 8, 1941, Serial No. 414,137

13 Claims. (CL. 179—1)

This invention relates to communication systems and more precisely to an improved system of "pseudo-extension." "Pseudo-extension" includes, for the purposes of this invention, the methods and means wherein an audio signal, at some point or at some time in its transmission either directly or indirectly to the ear, is modified so that, while all the composite frequencies present in the original audio signal are not present in the signal ultimately transmitted to the ear, the auditory perception is of a sound which has substantially all the sonant characteristics of the original signal.

A pseudo-extension circuit is defined as an electrical circuit for the transmission of the intelligence contained in a wide band of audio frequencies through a narrow band transmission channel, wherein the signal transmitted through the narrow band transmission channel is distorted by the addition to it of extraneous modulation and inter-modulation frequencies lying within the frequency range of said narrow band transmission channel.

One object of this invention is to provide a method and indicate means whereby signals which are modified and transmitted by a "pseudo-extension" circuit are improved in quality and rendered more pleasing to the listener.

Another object of this invention is to lessen unwanted and extraneous percussive and rasping sounds introduced in a signal by the "pseudo-extension" process of the present art.

Another object of this invention is to reduce the apparent auditory distortion resulting when a transmitted signal of transient nature is modified by the action of a non-linear transducer.

Another object of this invention is to reduce the apparent auditory distortion resulting from the inter-modulation of at least two signals at least one of which is transient in nature.

Further objects will be apparent from the description to be given.

Figs. 1 to 7 show a single frequency signal of a transient nature and the approximate frequency spectrums existent at various stages of the signal.

Fig. 8 shows a diagrammatic circuit of one embodiment of the invention as incorporated in a "pseudo-extension" non-linear circuit.

Fig. 9 shows, diagrammatically, an alternate circuit which may be employed to utilize the advantages of the invention.

Fig. 10 shows, schematically, a simplified cir-

cuit which may also be used to produce distortionless "pseudo-extension."

Fig. 11 illustrates a circuit including a frequency selective feed-back circuit, used to accomplish the object of this invention.

Fig. 12 illustrates an embodiment of this invention to retain or even accentuate the percussive quality of a signal.

Fig. 13 shows, in block diagram form, the use 10 of the circuits of Figs. 8 to 12, with associated apparatus in an improved "pseudo-extension" system.

Throughout the drawings, parts performing like functions have been given the same reference characters and numbers.

In order to clarify and facilitate the understanding of this invention, it is believed that an analysis of an elementary form of a signal wave of transient character would be serviceable. Accordingly, Fig. 1 shows such a wave.

In Fig. 1 is shown an arbitrary single frequency signal wave having a transient character. A single frequency is shown for convenience since by super-position of a plurality of 25 frequencies, signals of the type generally encountered in the transmission of audible sounds can be obtained.

This signal may be regarded as a single frequency only insofar as frequency is measured by 30 the reciprocal of the time between adjacent peaks of the same polarity. Actually every change in amplitude has associated with it an infinite number of side bands, provided that the intervals between amplitude changes are infinitely long. While this is the idealized case, nevertheless the side-bands encountered in practical cases may extend to the tenth harmonic of the fundamental frequency particularly in sharply introduced low frequency waves.

If the wave had an infinite interval of steady-state condition between amplitude variations then the side-bands would contain all frequencies or would be a continuous spectrum. In

45 other words, as the steady state interval approached infinity, the prime factor of the side-band frequencies would approach zero as a limit. An analysis of a practical case may be made by assuming that the single frequency is amplitude modulated by a frequency modulated signal, where the frequency modulation is the variations in the intervals between successive changes in amplitude. Therefore, in the practical case the prime factor of the side-band frequencies is the reciprocal of the time between the longest in-

tervals during which there is no amplitude change.

As the rate of increase or decrease of the amplitude of a wave such as that shown in Fig. 1 becomes slower and slower; the mean energy of the associated transients is shifted towards the lower frequencies. Simultaneously, the amplitude of the side-bands becomes less and less, until for steady-state conditions, the side-bands become zero.

Returning to Fig. 1, the wave is starting from a zero reference time in its build-up would, at some time t_1 have a frequency spectrum associated with it similar to that shown in Fig. 2. The side-bands are grouped about the steady state frequency f of the wave and their amplitudes are an inverse function of their displacement from frequency f .

At t_2 of Fig. 1, when the amplitude of the wave has almost reached a steady state value, the component frequencies have a spectrum similar to Fig. 3. It is to be noted that the side-bands have diminished in amplitude so that only those side-band frequencies in the immediate neighborhood of the steady-state frequency f have important amplitudes.

At time t_3 the illustrative wave is again changed in amplitude. The frequency spectrum consequently, due to this transient, becomes more complex and the frequencies more distantly removed from the steady state frequency f again become prominent. The spectrum assumes therefore, a complexity such as is shown in Fig. 4.

At time t_4 when the rate of increase of the envelope of the amplitudes has almost reached a steady-state condition, the magnitude of the side-bands has again diminished and, as before, only the frequencies in the neighborhood of the steady-state frequency f have important amplitudes. The frequency spectrum at this time is shown in Fig. 5.

At time t_5 after a relatively long interval the signal wave decreases suddenly in amplitude and immediately the side-band frequencies again appear. The spectrum of the side-band frequencies for this condition is shown in Fig. 6.

At time t_6 the amplitude of the arbitrary wave of Fig. 1 has diminished considerably and is approaching zero. The side-bands are therefore localizing in the immediate vicinity of the steady-state frequency f and as they localize, the amplitude of the frequency f drops off so that, when the wave of Fig. 1 has reached a practical zero magnitude, the side-bands have become merged into a position occupied by f which has in the meantime diminished and reached a zero magnitude.

Fig. 7 shows the spectrum analysis at time t_7 when the wave amplitude is approaching a practical zero value.

In general, prior art "pseudo-extension" circuits include as an essential element, a non-linear transducer. This non-linear transducer may be a square law detector, a class "C" amplifier tube, a combination of both, or any circuit having a non-linear input vs. output characteristics.

These prior art circuits, while producing a measure of "pseudo-extension" have associated with transients occurring in the input signal wave, an augmented percussive quality and a "raspy" harsh effect.

When the bass frequencies are "pseudo-extended" the effect noticeable on transients may be likened to the harshness associated with a scraping voice coil on a loud speaker or the sound

emanating from a cello or bass viol having a split or cracked body.

When the high frequencies are "pseudo-extended" this deleterious effect is particularly noticeable in speech when the fricative consonants are reproduced.

This invention describes definite methods and means for reducing the distortion encountered in prior art pseudo-extension processes. The circuits described hereinafter may also, with resulting improvement, be used in place of the non-linear circuit elements of the pseudo-extension system described in the applicant's co-pending U. S. application No. 348,359, filed July 30, 1940.

In order to explain the operation of this invention, an analysis of what happens when the arbitrary function of Fig. 1 is applied on a non-linear transducer, is advisable. Returning then, to a study of Fig. 1, let it be assumed that the wave represented thereby is applied to a modulator or non-linear element such as a square law detector, and, further that the transmission band of this latter device is also uniform between the frequencies f_1 and f_H .

The resulting frequency spectrum at time t_1 which appears in the output of the non-linear device is similar to that shown in Fig. 2 except that, due to the resulting inter-modulation products, the magnitudes of the side-bands are greatly increased; in other words, the spectrum is similar to that obtained if the original wave had been building up more rapidly at that time. The effect on the listener, hence, is that of a signal building up more rapidly and sharply than the original signal of Fig. 1 warranted.

Proceeding to a later time t_2 it is noted that at this time the signal has practically reached a steady state value, hence the frequency components at this time, as shown by Fig. 3 are grouped closely about the steady-state frequency f . The output of the non-linear device however, due to the inter-modulation frequencies introduced by its action, will produce a spectrum wherein the side-bands are greater in amplitude than those present in Fig. 3. That is, the spectrum resulting from the action of the non-linear device will at time t_2 actually be more nearly that shown by Fig. 2. Consequently, the ear, which if listening to the original wave would hear practically no transient effect, due to the action of the modulator, would detect a sizeable transient effect.

Thus it is evident that the introduction of a non-linear device will produce an exaggerated transient quality which persists after the transient quality of the original signal has been removed.

The methods and means for producing a "pseudo-extended" signal free from this abnormal duration of transient quality, which to the ear results in the presence of extraneous harshness and raspy effects, is the essence of this invention.

A similar analysis discloses the exaggeration and the lengthening of the duration of the transients at all transient points in the arbitrary function of Fig. 1 when a non-linear device is introduced in the signal circuit.

A time t_3 the spectrum of the output of the non-linear device will contain higher amplitude side-bands than those shown by Fig. 4, so that the resulting spectrum will be more nearly similar to that of Fig. 2.

At time t_4 , the spectrum of the modulator output will be more nearly similar to that shown in

Fig. 4, the amplitudes of the side-bands again having been increased by the non-linear characteristic.

At time t_5 the output of the non-linear device will have a frequency spectrum in which the side-bands are of much greater amplitude than indicated by Fig. 6.

At time t_6 the transient effect is again exaggerated by the non-linear device, so that the transient quality is still detectable even when the signal has approached a steady-state value and is leveling out in amplitude as it approaches a zero value.

Fig. 8 shows, diagrammatically, one circuit which may be used to accomplish the object of this invention.

The input signal is impressed across the terminal marked E_{in} . This signal, if the "pseudo-extension" is to be applied mainly to the bass frequencies, is preferably applied to the circuit thru a low pass filter F. A low pass filter of one section prototype constant K type having a cut-off frequency of about 100 cycles has been found satisfactory. The output of the filter is divided into two paths, the one to the left and consisting of C_1 ; R_1 ; R_2 ; T_1 ; R_5 and C_5 being the non-linear circuit; and the lower path, consisting of C_3 ; R_3 ; R_4 ; C_4 ; R_5 ; and T_2 is the control circuit.

The purpose of this control circuit is to change the bias of the tube T_1 so that T_1 operates as a non-linear device only when the signal wave applied to its grid has attained a relatively steady-state condition.

A portion of the signal from the output of the filter F is impressed, by means of the capacitor C_3 and the variable potentiometer R_3 , between the cathode and control grid of tube T_2 . Tube T_2 is biased by means of the battery E_{c2} to cut-off so that it operates as a class "C" amplifier. The plate potential for T_2 is supplied by the battery E_{b2} with polarity as indicated on the diagram.

Tube T_2 , being biased to cut-off, there is no potential ordinarily existing across the plate circuit load impedance R_4 and C_4 . When a signal is applied to the control grid of T_2 , current will flow in the plate circuit on the positive portions of the signal. The potential across R_4 however will not build up instantaneously in conformity with the control grid signal until the capacitor C_4 has charged. There is therefore, a time lag measurable from the time the incoming signal is applied to the control grid of T_2 and the time that a rectified potential appears across R_4 . This time lag is a function of the product of R_5 and C_4 for increasing signals, and a function of the product R_4 and C_4 for decreasing input signals.

The point where, on the increasing amplitude envelope of the input signal the tube T_2 begins to conduct can be adjusted by the setting of the potentiometer R_3 . The rate at which the rectified signal across R_4 decays when the input signal decreases is adjustable by varying either the value of C_4 or the value of R_4 .

The rectified signal appearing across R_4 is applied thru the battery E_{c1} , R_1 and R_2 to the grid of the tube T_1 . The battery E_{c1} is selected so that the operation of tube T_1 in the absence of a voltage across R_4 , is essentially a non-distorting linear amplifier. A positive voltage appearing across R_4 will destroy the bias of tube T_1 and cause it to operate as a grid leak detector or square law non-linear amplifier. The delay time of the networks $R_1 C_1$ and $R_2 C_2$ where C_2 is the

input capacity of tube T_1 may be made small in comparison to the time constants of $R_5 C_4$ and $R_4 C_4$ so that these latter constants will determine the build-up and decay respectively of the voltage applied to the grid of tube T_1 from the plate circuit of tube T_2 . For a transient associated with an increase in amplitude, the operation of the circuit of Fig. 8 is such that the tube T_1 operates as a linear device until the input signal has reached a relatively steady-state condition where after the tube T_1 operates as a non-linear device and continues to do so until a decay transient occurs in the input signal at which time the tube T_1 again operates as a linear amplifier.

The output E_{out} of T_1 , taken across its plate load R_6 through the blocking condenser C_6 , is therefore fairly free from distortion during the transient intervals of the input signal, and the extraneous, unpleasant and foreign auditory effects are eliminated from the "pseudo-extended" signal. This output may then be used in place of the uncontrolled output of the non-linear device associated with various "pseudo-extension" circuits.

The time constants of the delay circuits must be chosen with a view to the frequencies which are being impressed on the tube T_1 . Experimentally it has been found that satisfactory results are obtainable when the delay between the onset of the signal and the operation of T_1 as a non-linear device is, as a function of the mean frequency applied to the grid of tube T_1 , approximately

35 20 milliseconds for 200 cycles per second;
40 milliseconds for 100 cycles per second;
80 milliseconds for 50 cycles per second;
10 milliseconds for frequencies between 500 and 4000 cycles;
40 and about 40 milliseconds for frequencies higher than 5000 cycles per second. For decay transients, the tube T_1 should preferably be returned to its linear operation as soon as the decay transients set in; an approximate time being 8 to 10 milliseconds.

Another embodiment of this invention is shown in Fig. 9. This circuit accomplishes the object of this invention in one possible alternate manner. The signal to be "pseudo-extended" is applied to the input of the filter F. This filter may, if the low audio frequencies are to be operated upon, have the same characteristics as that described in connection with the circuit of Fig. 8. If the high frequencies are to be "pseudo-extended" then a single stage high pass constant K prototype having a cut-off frequency of approximately 2500 cycles has been found satisfactory. The output of the filter F is applied to an electronic compressor circuit of the type well known to the art, consisting of tubes T_3 , T_4 and the double diode T_5 . The operation of this compressor circuit is as follows. The signal from the output of the filter F is applied by means of the condenser C_6 and the grid resistor R_7 to one control grid of a two control grid pentode T_3 . The amplified signal appearing in the plate circuit of T_3 is impressed by means of the condenser C_7 to a class "A" amplifier T_4 ; the level of the signal at the grid of T_4 being adjustable by means of the potentiometer R_8 . The amplified signal appearing in the plate circuit of T_4 is applied through the audio transformer T_{R1} to a double diode rectifier T_5 . A rectified signal appears across the diode load resistance R_4 , the rate at which it builds up being determined by the product of the series re-

sistor R_4 and the capacitor C_4 . This rectified voltage is applied to the second control grid of T_3 and being a negative voltage, decreases the transconductance of the tube T_3 resulting in a decrease in the signal appearing in the plate circuit of T_3 . The amplitude changes in the input signals are therefore minimized. The output of the tube T_3 is impressed, through the audio transformer T_{12} , on the tube T_1 . This tube is arranged with a small negative bias furnished to its control grid by the battery E_{Cl} . The resistance R_2 is inserted in series between one terminal of the secondary of the transformer and the control grid of tube T_1 .

When the signal applied to the grid of tube T_1 is greater than its bias potential, grid current will flow through the resistance R_2 causing the transconductance of the tube to decrease. The tube will consequently act as a non-linear device. By using a tube for T_3 which has a remote cut-off characteristic for the grid to which the diode rectified voltage is applied, the compressor circuit can be made to suppress transients above a certain amplitude of input signal.

The bias of tube T_1 is adjusted so that tube T_1 acts as a non-linear device when the amplitude of the input signal to the compressor circuit has reached an amplitude beyond which further increases are minimized.

The selection of the time constants associated with the diode load should be chosen so that the ripple voltage appearing across the diode load and applied to its associated grid of T_3 is approximately ten per cent of the signal voltage applied to the other grid of T_3 . This condition holds for the charging time of C_4 through R_4 and the associated closed circuit and for discharge time of C_4 as determined by the value of R_4 , and the equivalent shunt impedance across C_4 due to the associated shunt meshes.

The output voltage E_{out} is taken from the plate circuit load resistor R_4 through the blocking condenser C_5 .

The circuits of Fig. 8 and Fig. 9 show two embodiments of the invention, and in addition they illustrate two different solutions to the problem of the elimination of transient distortion in a non-linear device.

The first circuit, that of Fig. 8 varies the linearity of the non-linear device so that it operates essentially as a class "A" amplifier during the time that a transient is impressed on its input. The second circuit arrangement, that of Fig. 9, is illustrative of that class of circuits within the scope of this invention wherein the transients are minimized at those times when the non-linear device operates as such.

In the circuit of Fig. 10 is shown another possible alternate arrangement to produce the object of this invention.

If a signal is suddenly applied to a transducer having a narrow acceptance band, such as a tuned resonant circuit, the build-up of the signal in the output of the transducer is very slow. In other words, a sharply increasing or decreasing amplitude will not be effective as such in the output of a transmission network having a narrow frequency acceptance band.

This property of a tuned circuit may be used to prevent sharp onset and decay transients with their associated side-bands from producing, in the output of a non-linear device, the characteristic transient distortion of the prior art "pseudo-extended" signals.

In Fig. 10 the signal to be impressed on the

non-linear device of a "pseudo-extension" circuit is designated at E_{in} . This signal is divided into two channels, the first of these is applied through the volume control R_{18} to one control grid of a mixer tube such as the present day 6L7, designated as T_{13} . The other channel is applied to a tuned circuit T_c tuned to the region of the frequencies which are to be "pseudo-extended." When the high frequency spectrum of a signal is to be transmitted over a transmission circuit having a low pass characteristic extending only to say, 4000 cycles, satisfactory results have been obtained with a resonance circuit for T_c tuned to about 6000 cycles. If the low frequency spectrum of a signal is to be transmitted over a circuit having a high pass characteristic extending to, for example 120 cycles, the tuned circuit T_c should be tuned to the neighborhood of 60 cycles.

The narrow band output of the tuned circuit T_c is amplified by a linear amplifier designated as "A" in Fig. 10.

The output of the amplifier "A" is applied to the second control grid of the mixer tube T_{13} and across the grid resistance R_{17} . The "mixed" signals appearing across the plate load resistance R_{16} of tube T_{13} are applied, through the blocking condenser C_{11} , to the terminals of resistor R_{18} and then, through the grid leak resistance R_2 applied to the grid of tube T_1 . Tube T_1 is given a slight initial grid bias by means of the self biasing network in its cathode circuit. Tube T_1 will operate, by virtue of the initial bias, as a class A amplifier for small signals applied to its grid. The volume control R_{18} is adjusted so that the signals appearing at the grid of T_1 via the first channel, that is, impressed on the first control grid G_1 of T_{13} , are of sufficiently low magnitude so as to be amplified by T_1 without distortion.

The amplifier "A" contained in the second channel, namely that channel impressed on the second control grid G_2 of tube T_{13} , causes an amplified second channel signal to be impressed, via T_{13} on the control grid of tube T_1 . This signal, by circuit design, is made approximately ten times the magnitude of the first channel signal impressed on the grid of T_1 . The tube T_1 therefore acts as a non-linear device in the presence of a signal from the second channel.

The signal appearing across the plate load resistor R_{16} of tube T_1 is utilized, through condenser C_5 , as the output of the non-linear circuit in prior art "pseudo-extension" circuits.

The circuit of Fig. 10 described above and the circuit of Fig. 11 to be described operate to prevent transient distortion by a non-linear device basically by subduing the transient. This is accomplished by slowing up the onset and the decay of transients so that the side bands associated with the transients are reduced in amplitude to a value small in comparison to the amplitude of the steady state frequency component. Therefore when this restricted transient signal is applied to a non-linear device, the side-band frequencies associated with the transients are of insufficient magnitude to produce extraneous inter-modulation components. The output of the non-linear device therefore is relatively free from the harsh, rasping, spuriously fricative sounds associated with prior art "pseudo-extended" signals.

Fig. 11 illustrates a circuit which may be used to realize the utility of this invention. Basically, its operation is similar to that of Fig. 10 but it is shown in order to indicate one of a large number of modifications which are within the scope of

this invention, and which utilize the method and means described herein.

Referring to Fig. 11, E_{in} is an audio signal containing the frequencies which are to be "pseudo-extended." This signal E_{in} is applied to one grid G_1 of two control grid pentode T_{14} of the present day 6 L7 type. R_7 is the grid resistance to maintain the bias on grid G_1 . The tube is biased so as to operate as a linear amplifier by the conventional self-biasing by-passed cathode resistor arrangement as indicated in the figure.

An amplified signal appears across the plate load resistor R_{20} of tube T_{14} . Those frequencies appearing in this amplified signal which are to be "pseudo-extended" are fed-back through the blocking condenser C_{11} and the network $R_{23}, C_{13}, R_{22}, C_{12}$ to the second grid G_2 of the tube T_{14} . The network $R_{23}, C_{13}, R_{22}, C_{12}$ is selected so as to produce an approximate phase shift of 180 degrees for these frequencies.

The potentiometer is used to control the voltage of the "fed-back" signal so as to prevent oscillation. The phase of this "fed-back" signal being such that regeneration will occur for frequencies to be "pseudo-extended," the tube T_{14} will therefore selectively amplify these frequencies to a much greater extent than other frequencies present in the signal E_{in} . Effectively therefore the tube T_{14} acts as a tuned amplifier having a maximum gain in the neighborhood of the frequencies to be "pseudo-extended." The principle of operation of the circuit of Fig. 10 and that of Fig. 11, is similar, that is, in Fig. 11, due to the relatively sharp frequency characteristic of the tube T_{14} and its associated feed-back circuit, the side-bands present during changes in amplitude of the preferentially amplified signal are limited in amplitude. Limiting the number and amplitude of these side-bands produces, after the thus restricted signal is acted upon by the modulator or non-linear amplifier tube T_1 , a signal wherein the intermodulation products due to these side-band frequencies are reduced in number and in amplitude. Therefore, the resulting signal produces an apparently undistorted effect upon the listener.

The signal appearing across the plate load resistor R_{20} is impressed, through the blocking condenser C_{11} to the potentiometer R_1 . The setting of the potentiometer is adjusted so that, in absence of a regenerated signal across its terminals, the ordinarily amplified voltage is insufficient to drive the tube T_1 off the linear portion of its grid voltage-plate current characteristic as determined by the grid bias produced by the cathode resistor R_{24} by-passed by the condenser C_{14} .

When a regenerated signal is present however, the tube T_1 , due to the much larger voltage of this signal, will, and aided in this direction by the grid resistor R_2 , act as a non-linear device and produce inter-modulation and harmonic components in its plate circuit. The signal appearing across the plate load R_{18} is utilizable in place of the output of the non-linear device of the related prior art circuits.

In certain audio transmission systems it is often desired to "pseudo-extend" the audio signal but also transmit, together with the processed signal, the full percussive and transient quality of the original signal. The suppression of the transients associated with the original signal before processing, results in the loss of a certain amount of articulation in speech and the loss of clangor and percussion generally associated with some sounds.

Fig. 12 shows, diagrammatically an arrangement of a circuit utilizing the novelty of this invention which may be used to retain the or even augment the transient quality of a signal and yet avoid the harsh and fricative sounds due to the prolongation of the transient state of a signal due to the action of a non-linear transducer. In Fig. 12, the signal E_{in} to be "pseudo-extended" is impressed on the input of the filter section F . This filter section may be a single stage constant K prototype or its equivalent. If the circuit is to be used to "pseudo-extend" the high frequency spectrum of the signal E_{in} , the filter F is arranged as a high pass, a representative cut-off frequency being 3000 cycles. If the circuit is to operate for base frequencies, the filter F may be a low pass having a cut-off frequency of about 120 cycles.

The output of the filter F in either case is impressed on the grid of a linear amplifier tube T_6 , R_7 being the conventional grid resistor associated with the grid circuit of T_6 . The amplified signal appearing in the plate circuit of tube T_6 is divided into three channels consisting of two control circuits and one main circuit.

The main circuit, by means of the transformer TR_3 having two secondary windings, is further divided into two secondary circuits. The first of these secondary circuits is impressed through the grid resistance R_{12} to the grid of the tube T_{11} . The second of these secondary circuits is impressed through the grid resistance R_{13} to the grid of the tube T_{12} .

The lower control circuit consisting of R_8, T_7, TR_6 and T_8 controls the non-linearity of the grid voltage vs. plate current characteristic of the tube T_{12} .

When the input signal E_{in} is suddenly increased in amplitude, that is, becomes transient in nature, the amplified portion of this signal which is impressed through the blocking condenser and the potentiometer R_8 to the grid of the linear or class A amplifier tube T_7 appears as an amplified signal in the plate circuit of T_7 . This plate circuit signal is coupled by means of the audio transformer TR_6 to a full wave diode rectifying tube T_8 . The rapidity with which the resulting rectified voltage appears across the diode load R_9, R_{10} and C_9 is determined by the charging time of the condenser C_9 through the series resistor R_9 . For an instant, therefore upon the sudden onset of a transient signal no voltage appears across the resistor R_{10} . The potential of the junction of R_9 and R_{10} is therefore during this instant, the same as the potential of the ground or common connector. As the condenser C_9 charges, the potential at the junction of R_9 and R_{10} becomes increasingly negative with respect to the common connector and therefore also with respect to the cathode of the tube T_{12} .

The tube T_{12} having no grid bias except that available from the junction of R_9 and R_{10} through the lower secondary of the transformer TR_3 , will therefore, during the first instant of the sudden onset of the input signal E_{in} , operate as a non-linear device. The augmented transient side-bands due to the inter-modulation frequencies are introduced by the tube T_{12} during the interval wherein its grid has a zero bias with respect to its cathode. The next instant after the onset of the signal, the negative voltage appearing at the junction of R_9 and R_{10} and applied through R_{13} to the grid of T_{12} establishes a negative bias on this grid and causes the tube T_{12} to act as

a linear or class "A" amplifier. The signal appearing in the plate circuit of the tube T_{12} is then applied to the output through the audio transformer TR_5 .

The upper control circuit consisting of R_{11} , T_9 , TR_4 and T_{10} controls the grid bias of the tube T_{11} . The tube T_{11} is biased by the battery E_{c4} so as to operate, in the absence of a voltage across the load resistor R_{15} of the rectifier T_{10} , as a linear or class "A" amplifier. When the input signal E_{in} is suddenly applied, it is amplified by the tube T_6 and that portion of it appearing on the grid of T_9 is amplified further, and, by means of the audio transformer TR_4 , is applied to the diode T_{10} through the rectifier load impedance R_{14} , C_{10} and R_{15} . The condenser C_{10} charges slowly through the limiting resistor R_{14} and as it charges, the potential of the cathode of the rectifier T_{10} gradually rises with respect to ground. The cathode is connected through the battery E_{c4} , the upper secondary winding of the transformer TR_3 and R_{12} , to the grid of the tube T_{11} . Consequently as the cathode of T_{10} rises in potential in a positive direction, the voltage of the battery E_{c4} is gradually counteracted and the negative bias of the tube T_{11} is gradually destroyed. As the bias of T_{11} is destroyed the grid operates with too little bias and finally without bias so that the tube T_{11} will operate as a non-linear device similar to a grid leak detector. R_{12} , a resistance in the grid circuit provides an additional voltage drop across it when, on the positive halves of the main channel signal, grid current flows in the grid circuit of the tube T_{11} . This action biases the grid more heavily at these times and accentuates the non-linearity.

The signal appearing in the plate circuits of tubes T_{11} and T_{12} is impressed across the upper and lower halves respectively of the output transformer TR_5 . The composite signal appearing across the secondary of this transformer TR_5 is designated on the figure as E_{out} and is utilized in place of the output of the non-linear device in the prior art "pseudo-extension" circuits.

The operation of the circuit of Fig. 12 on a time sequence basis is thusly; when a signal is suddenly applied to the input (E_{in}) an amplified signal containing a plurality of side-bands appears in the plate circuit of T_{12} . (Also, during the first instant, an amplified undistorted signal appears in the plate circuit of T_{11} . These signals are combined in the transformer TR_5 and are available across the output terminals of TR_5 . Gradually, after the first instant, the plate circuit signal of T_{12} becomes undistorted, as a negative potential builds up across R_{10} and C_9 ; at which time the plate circuit signal of T_{11} is still relatively undistorted since the condenser C_{10} is still only partially charged. The signal E_{out} is therefore relatively undistorted for an interval after the first, after which, when C_{10} has charged sufficiently to cause the voltage across it to counteract the initial grid bias of T_{11} , the plate circuit signal of T_{11} becomes distorted producing intermodulation between harmonic components of those frequencies impressed on its grid.

The plurality of elements involved in the circuit of Fig. 12 make it inadvisable to fix precise circuit constants for its operation. The time constants of the various complicated and interconnected meshes would render the synthesis of the circuit extremely laborious and difficult. Accordingly, a simple method of adjustment has been evolved.

A power amplifier with an associated filter is connected across the secondary winding of TR_5 . The characteristics of the filter should approximate the frequency characteristic of the limited frequency acceptance band of the apparatus through which the "pseudo-extended" signal is to be transmitted. To the output terminals of the power amplifier and filter is connected a loud speaker. This auxiliary apparatus is shown on Fig. 12 by the dotted lines, PA being the power amplifier, FX being the filter and LS being the loud speaker. The vertical plates of a cathode-ray oscilloscope are connected between the plate of T_{11} and ground.

A monotone signal whose frequency lies approximately midway in the frequency band of the signal which is to be "pseudo-extended" is abruptly applied and removed intermittently to the input E_{in} of the circuit of Fig. 12. The setting of R_{11} and the value of the variable resistance R_{14} are adjusted simultaneously to a point where while the cathode ray oscilloscope deflection appears to be unilateral, sharp clicks are not heard in the loud speaker upon the application and removal of the input signal.

After this is done, the shorting lead between the grid of T_{12} and its cathode is removed and the setting of R_8 and R_9 adjusted so that a click is evident in the loud speaker upon the application and removal of the input signal. R_8 and R_9 are adjusted so that the clicks thus introduced should be comparable in quality and duration to those which are obtained when the intermittent signal is applied directly to a loud speaker having a wide band response.

As heretofore stated and described, this invention provides methods and means for producing a "pseudo-extended" signal which is relatively free from transient distortion and devoid of the exaggerated and prolonged transient quality apparent as distortion, these unpleasant sounds being present to a noticeable degree in prior art "pseudo-extended" signals. In other words, by the use of the circuits herein described, a sound having a wide audible frequency spectrum may be transmitted to a listener over a transmission link having a narrow frequency pass characteristic, and while the sound reaching the listener's ears does not contain a wide band of audible frequencies, nevertheless, the effect is substantially the same as though all the audible frequencies contained in the original sound were available, without distortion, to the listener.

To produce this "pseudo-extension" effect obviously the representative circuits of Figs. 8 to 12 must be used in conjunction with a sound source, microphone, phonograph record or other primary or secondary sources of audio signals and necessary signal levels produced with the aid of amplifier or attenuators, active and passive transducers, all of which are well known to the art.

In order to indicate more clearly the auxiliary circuits and apparatus necessary in the improved "pseudo-extension" system of this invention the representative diagram of Fig. 13 is shown.

Fig. 13 shows, in block diagram form, since the elements thus shown are well known to the art, the utilization of this invention to one of many possible and varied applications. The system of Fig. 13 shows the use of the method and means of this invention to the transmission of sounds by a radio system. S is a source of audible sound as for example an orchestra. The sounds emanating from this source are intercepted by the microphone and after conversion to an elec-

trical audio signal are amplified by the amplifier AMP. The output of this amplifier is applied to the improved "pseudoextension" system PEC, subject of this invention. The output of the amplifier AMP is considered as the input E_{in} of the representative circuits of Figs. 8 to 12 shown herewith. After being modified by the circuit means of this invention, the resulting output signal E_{out} is impressed and used to modulate a radio frequency carrier in the usual manner in the radio transmitter XT. The portion of the transmission link having a restricted frequency pass characteristic may be anywhere in the entire transmission link beyond the output of the circuit PEC, and may even be due to a hearing deficiency in the ultimate listener. If there are no frequency limitations in the transmission link but restricted side-band radio transmission is desired, the filter F_x of Fig. 13 may be interposed in the transmitter circuit.

In applications where the magnitude of the original sound source falling within the transmission band is not sufficient to produce a balanced or realistic signal to the listener, a part of the output of the amplifier AMP may be bypassed around the "pseudo-extension" circuit and recombined with the modified signal appearing in the output of the PEC circuit as shown in the figure.

The signal transmitted by the station XT may then be received by an ordinary receiver such as RE of Fig. 13, without requiring circuit modifications in that receiver.

The process of "pseudo-extension" need not be limited so as to obtain a signal containing as an example frequencies from 120 cycles to 10,000 cycles per second and between which limits are included the intermodulation and harmonic products of frequencies lower than 120 cycles; nor need it be limited to producing a signal containing, as a further example, frequencies from 30 to 4000 cycles per second with the intermodulation products of frequencies higher than 4000 cycles per second. For, by operating on the transient portions of the signals as described above, additional intelligence and a more pleasing signal can be produced by operating on any or all of the frequencies associated with a signal. More specifically, the middle register of a signal, that is, those frequencies in a signal falling within the narrow acceptance band of a transmission link may be operated upon by the procedure disclosed herein and a more pleasant and more realistic signal will result. When these latter frequencies are operated upon, the resulting signal is given more sonority and fullness, similar to an effect producable by increasing the amplitude of a sound to loud intensities.

In addition, the introduction of both the highest and lowest frequencies simultaneously into the "pseudo-extension" circuit as described heretofore will result in an increase of quality and articulation conveyed by the resulting signal when transmitted through a system whose acceptance band extends only through a middle range of frequencies. This is so since the intermodulation of the highest with the lowest frequencies will result in inter-modulation products outside the acceptance band of the subsequent transmission circuit.

Since this invention can be used to operate on a wide range of input signal frequencies, the input filters which determine the range of signal frequencies to be "pseudo-extended" have, in Figs. 10 and 11, been omitted. This has been

done to emphasize the point that the input filter F of Figs. 8, 9 and 12 is not necessarily an indispensable feature of the circuits shown herewith.

The class of circuits shown in Figs. 8 to 12 may be used similarly to those recognized as prior art circuits, yielding in the place of the latter an improved and undistorted result. Obviously, therefore, these circuits and the principles governing their operation can be used in conjunction with the "consonator" circuit described in my co-existing application.

Other embodiments will be evident to persons familiar with the pertinent art, without departing from the spirit or scope of my invention. As an example, an equivalent method might be used, and the results be substantially the same, if the circuits were made to operate on a carrier frequency modulated by the audio signal to be "pseudo-extended," in which case while the operations would be performed at a different range of frequencies, the method and means would be substantially the same as indicated herein. The illustrations included herewith and the descriptions included herein should serve, in view of the entire disclosure, to indicate rather than limit the general design, and to illustrate rather than specify the components and elements of the various representative circuits since many modifications may be made without departing from the scope of my invention as set forth in the appended claims.

What I claim is:

1. In a "pseudo-extension" circuit including a non-linear device and a source of audio frequency modulation, means for impressing said audio frequency modulations upon the input of the non-linear device, means for varying the non-linearity of said non-linear device during changes in the amplitude of the impressed signal, means for collecting at least a part of the output of said non-linear device, and means for transmitting the collected signal.

2. In a "pseudo-extension" circuit including a non-linear device and a source of audio frequency modulations, means for dividing the audio frequency modulations into two channels, means for selecting a part of the frequencies contained in the first of these two channels, means for impressing said selected part of the first channel on the input of the non-linear device, means for varying the non-linearity of said non-linear device during changes in amplitude in the input signal impressed on said non-linear device, means for combining the output signal of said non-linear device with the signal of the second of the two channels, and means for transmitting at least a part of the combined signal.

3. A method of increasing the apparent frequency range of a transmitted audio signal comprising the steps of: selecting at least a part of the audio signal modulations, limiting the changes in amplitude envelope of the selected signal by the action of a compressor circuit so as to produce substantially a constant amplitude frequency distortionless signal, impressing the thus limited audio signal on the input of a non-linear device, and collecting and transmitting at least a part of the output of said non-linear device.

4. A method of increasing the apparent frequency range of a transmitted audio signal comprising the steps of: selecting at least a part of the audio signal modulations, limiting the changes in amplitude of the selected signal by the action of a compressor circuit, impressing the

thus limited audio signal on the input of a non-linear device, varying the non-linearity of the non-linear device during changes in amplitude of the signal impressed on its input, and collecting and transmitting at least a part of the output of the thusly varied non-linear device.

5 5. A method of increasing the apparent frequency range of a transmitted audio signal according to claim 3, in which an unmodified part of the input signal is combined and transmitted together with the collected and transmitted part of the output of the non-linear device.

10 6. A method of increasing the apparent frequency range of a transmitted audio signal according to claim 4, in which an unmodified part of the input signal is combined and transmitted together with the collected and transmitted part of the output of the varied non-linear device.

15 7. A method of increasing the apparent frequency range of a transmitted audio signal comprising the steps of: selecting at least a part of the audio signal modulations, increasing the relative amplitude of a portion of the frequencies contained in said selected part, impressing the distorted signal thus resulting on the input of a non-linear device, and collecting and transmitting at least a part of the output signal of said non-linear device.

20 8. A method of increasing the apparent frequency range of a transmitted audio signal comprising the steps of: selecting at least a part of the audio signal modulations, increasing the relative amplitude of a portion of the frequencies contained in said selected part, impressing the resulting distorted signal on the input of a non-linear device, varying the degree of non-linearity of said non-linear device during changes in amplitude of the original audio signal, and collecting and transmitting at least a part of the output signal of the varied non-linear device.

25 9. A method of increasing the apparent frequency range of a transmitted audio signal according to claim 7, in which at least a part of the unmodified original input signal is combined and

transmitted together with the collected and transmitting part of the non-linear device.

10 10. A method of increasing the apparent frequency range of a transmitted audio signal comprising the steps of: dividing the audio signal into two channels, impressing the first of these two channels on the input of a non-linear device, varying the non-linearity of the non-linear device during the initial time of a change in amplitude of the signal of the first channel, impressing the signal of the second of the two channels on the input of a second non-linear device, varying the non-linearity of this second non-linear device during a change in amplitude of the signal of the second channel, collecting at least a part of the signals appearing in the outputs of both non-linear devices, and combining and transmitting said collected parts.

15 11. A method of increasing the apparent frequency range of a transmitted audio signal according to claim 8, in which an unmodified part of the original signal is combined and transmitted together with the collected and transmitted parts of the outputs of the non-linear devices.

20 12. In a system of the class described, the combination with a non-linear device comprising means for varying the non-linear characteristic of said non-linear device during the times when the signal impressed on the input of said non-linear device is undergoing a change in its amplitude envelope.

25 13. In a system of the class described, the combination with a non-linear device comprising means for impressing an audio signal upon the input of said non-linear device, means for varying the characteristic of said input device so as to secure in its output a signal that is substantially undistorted during the intervals in which said impressed audio signal is transient in character, means for combining the output of said non-linear device with other audio signals and means for transmitting the thus combined signal.

LOUIS A. DE ROSA.
